UNITED STATES PATENT OFFICE.

CHARLES EUGENE LANG, OF LOS ANGELES, CALIFORNIA.

RETRIEVING-TROLLEY.

1,109,234.

Specification of Letters Patent.

Patented Sept. 1, 1914.

Application filed June 22, 1908. Serial No. 439,878.

To all whom it may concern:

Be it known that I, CHARLES EUGENE LANG, a citizen of the United States, residing at Oakland, in the county of Alameda and State of California, have invented a new and useful Retrieving-Trolley, of which the following is a specification.

This invention relates to an overhead trolley for electric railway cars which, in case 10 of escape from the trolley-wire, will automatically lower to a position below the level of the trolley-wire and span wires, and which can be returned to operative position by simple manipulation by the conductor or other attendant.

An object of the invention is to provide means whereby the trolley-pole will be started on its way to its lowered position by the springs which normally hold it 20 against the trolley-wire and which lift the pole to the position from which it will be returned by the force of said springs assisted by gravity.

The invention comprises the retrieving 25 trolley, and the parts and combinations of parts hereinafter more particularly described.

It is a principle of the operation of this invention that the trolley-pole is normally 30 forced upward by the lifting means, as one or more springs, and thereby pressed against the trolley-wire, and said pole while restrained from sudden upward movement is free to rise and lower to accommodate the 35 trolley to the different heights of the trolley-wire above the car; but in case the trolley-pole is so unrestrained as to allow it to suddenly rise, parts are released while the pole is within its normal working range to 40 allow the trolley-pole to bodily descend by gravity, and the force of the springs operates for an instant to start the trolley-pole downward.

I do not limit myself to the specific construction shown, as changes within the scope of the appended claims are contemplated.

An object of the invention is to limit to a minimum the upward travel of the trolley at any time it leaves the trolley-wire. This 50 object is in a measure accomplished by making provision whereby the tripping of the trolley-pole for its return is accomplished by a quick upward movement regardless of the position from which the trolley starts.

55 In practice, provision is made whereby the

rapid upward movement of the trolley after it leaves the wire will effect the release of the trolley-pole before the trolley-wheel has traveled to exceed twelve inches, regardless of the height from which the trolley-wheel starts.

Another object of the invention is to leave the trolley free to swing so long as it is in operative position, and to lock the same against swinging laterally when out of operative position, so as to avoid all danger of striking any object at the side of the track.

An object of the invention is to so construct and arrange the trolley pole carrying and supporting devices that the force which sustains the trolley-pole is at one time applied in such a direction as to lift the trolley-pole, and at another time is applied in such a direction as to be ineffectual to lift the pole, but may be effectual to cushion the pole against too great descent.

A further object is to avoid any strong tension on the pole-lifting springs when the trolley is out of commission, thus doing away with the bending of the pole which is common with trolleys of the present construction in cases where a car is provided with two oppositely-directed trolley poles, one of which is fastened down while the other is in commission.

Other objects and advantages may appear from the subjoined detailed description.

The accompanying drawings illustrate the invention in the form at present deemed most desirable.

For convenience of illustration the figures are not all on the same scale. Figures 1, 4, 6, 8 and 9 are on one scale; Figs. 2, 3, 5 and 7 are on a larger scale; Figs. 10, 11, 12, 13 and 14 are on a still larger scale; and Figs. 15, 16, 17, 18 and 19 are on a common scale practically twice that of Fig. 1.

Fig. 1 is a side elevation of a trolley embodying this invention mounted for operation on a railway car, a portion of which is shown. The trolley is shown in solid lines *a* in that position at which it comes to rest after the trolley-wheel has escaped from the trolley-wire. Four other positions are shown in dotted and broken lines. The five positions shown are respectively lettered *a*, *b*, *c*, *d*, *e*; the position *b* being that to which the trolley-pole will be drawn from resting position *a* by the attendant in order to bring the parts into the positions at

which the elevating means become effective to raise the trolley-pole. The position *c* is the normal working or running position with the trolley-wheel against the trolley-wire. The positions *d* and *e* indicate positions at which the trolley-wheel and pole may successively change direction of movement when the unrestrained trolley-wheel has left the trolley-wire. The position *e* is that from which the pole and wheel return to resting position *a*. Arrows indicate the course of the trolley-pole. Fig. 2 is a plan on a larger scale of the trolley-base and foot detached with latch and latch-spring in place. Fig. 3 is an inverted view on the scale of Fig. 2 of the parts shown in Fig. 2. Fig. 4 is a broken elevation from the left of and on the scale of Fig. 1 with parts in operative position, *c*. Fig. 5 is a sectional elevation on the scale of Fig. 2 looking toward the left from line indicated at x^5-x^6 , Figs. 1, 10 and 11. Fig. 6 is a view on the scale of Fig. 1 looking toward the right from said line x^5-x^6 , with the pole in position *b* shown in solid lines in Fig. 11. Fig. 7 is a fragmental elevation on the scale of Fig. 2 looking toward the right from a line approximately indicated at x^7-x^7 , Fig. 12. Some of the parts are shown in section on said line x^7-x^7 . Fig. 8 is a mid-sectional elevation on the scale of Fig. 1, showing the trolley-foot detached, viewed from line $x^{11}-x^{12}$, Figs. 2, 3, 10 and 14. A heel-piece, its pivot and the trolley-fulcrum is also shown. Fig. 9 is a detached view on scale of Fig. 1, showing the inside of one of the trolley-base sections. Fig. 10 is a fragmental plan on a scale greater than that of the preceding figures with parts shown in setting position *b*. Fig. 11 is a vertical longitudinal mid-section on line $x^{11}-x^{12}$, Figs. 2, 3, 10 and 14, on scale of Fig. 10. The parts are shown in solid lines in setting position *b*. The positions *a* and *c* are indicated in broken and dotted lines respectively. Parts are broken to expose the connection between a crank and spring. Fig. 12 is a section on said line $x^{11}-x^{12}$, scale of Fig. 10, showing in solid lines the tripping position *e* which the parts assume just before returning to the resting position *a*. Broken lines indicate a working position *c* and a retrieving position *d* from which the parts may have moved to said tripping position *e*. Fig. 13 is a section on line $x^{13}-x^{13}$, Figs. 10 and 14; scale of Fig. 10. The parts are shown in the working position *c* from which the parts may move to retrieving position *d* and on to tripping position *e* shown in solid lines in Fig. 12 and thence to resting position *a* shown in broken lines in Fig. 11, from which the trolley-pole may be drawn down to resetting position *b*. Fig. 14 is a plan section on line $x^{14}-x^{14}$, Figs. 12 and 13; scale of Fig. 10. Figs. 15, 16, 17, 18 and 19 are kinematic

views illustrating the operation of the appliance throughout a full cycle. Fig. 15 shows the operative or working position *c*; Fig. 16, the retrieving or topmost position *d* between the operative position *c* and the tripping position *e*. Dotted lines indicate the tripping position and the retraction effected by the force of the spring just after the trolley has moved up from the wire. The trolley pole in Figs. 15 and 16 is broken between the lugs 33 and the trolley wheel to contract the view. Fig. 17 shows the tripping position *e*; Fig. 18 represents the resting position *a*; and Fig. 19, the resetting position *b* to which the parts may be drawn from position *a* by the attendant, and in which position the lifting springs become effective to return the pole to the operative position *c*, shown in Fig. 15. In Figs. 18 and 19 the width of the trolley fulcrum slots is exaggerated to avoid confusion.

Corresponding characters indicate corresponding parts in the several views. Some of the parts which are practically duplicates of other parts are distinguished by the use of the same character with the addition of an exponent.

In considering this invention the duplicate parts may be generally regarded as singular the main purpose of the duplication being to give proper balance and strength with minimum size and weight of parts.

1 designates a car; 2, an insulating trolley foundation thereon. 3 is a trolley-pole; 4, a trolley-wheel; 5, a trolley-wire, all of the usual construction.

6 is a divided cast metal trolley-base formed of two semicircular sections 7, 7', fastened to each other by bolts 8 and to the insulation 2 by bolts 9.

10 is a trolley-foot antifrictionally supported in the base 6 by antifriction balls 11 which run in two annular grooves 12, 13, in the base and trolley-foot respectively. The trolley pole is pivotally mounted as hereinafter set forth and is carried by the foot. Said grooves are semicircular in cross-section and register with each other so that when the semicircular sections 7, 7' of the trolley-base are brought nearly together on one side of the trolley-foot and are yet spread far enough apart at the other side to receive the antifriction balls 11, said balls may be inserted one by one into the annular race-way therefor formed by the grooves, until such race-way is appropriately filled with balls. The number of balls employed is preferably less than is sufficient to fill the race-way; for instance, if the race-way is capable of containing forty balls, thirty-six balls may be inserted, thus leaving plenty of play and insuring a satisfactory distribution of the balls around the race-way. The balls substantially correspond in diameter with the race-way so

that there will be a true antifriction support against all strains in every direction, without liability of rattling.

14, 14' designate two standards projecting upwardly from the trolley-foot 10, and each provided with four holes 15, 16, 17, 18.

19 is a heel journal supported in the holes 15.

20 is the trolley fulcrum or heel-pin extending through the holes 16 which are in the form of horizontal slots to allow the forward and backward play of the trolley-fulcrum or heel-pin 20.

21 is a spring-crank shaft journaled in the holes 17, and 22 is a latch-lever-pin journaled in the holes 18.

The trolley pole is shiftably mounted on a heel that is shown as constructed of two duplicate parts 23, 23', pivotally mounted outside the standards 14, 14', by the heel-journal 19 to carry the trolley-fulcrum pin 20 on which the shank 24 of the trolley-pole 3 is fulcrumed. The shape and arrangement of the duplicate parts 23, 23', which together constitute the heel, may be noted by reference to Figs. 7, 8, 11 and 12. In Fig. 7 the front edges of said duplicate parts are shown. In Fig. 8 the outline indicated at 23 corresponds to the outline for the side of 23', not shown, in this view. In Figs. 11 and 12 such side outline may also be traced. Said duplicate parts are arranged in parallel planes on a common axis from which they extend downward to be latched by a latch 28 hereinafter described, and upward to form the support of the trolley fulcrum 20. The two parts 23, 23' are not connected together rigidly but they work as a unit and are the equivalent of a single piece. The heel thus formed of the two parts 23, 23' is kinematically, an integral element and is formed in two parts, in the instance illustrated, for convenience of manufacture and for strength and stability. The slots 16 in the standards allow a limited forward and backward movement of the trolley-fulcrum 20 on which is journaled a roller 25 arranged to engage an arm 26 that is fixed to and extends downwardly and rearwardly from the spring crank shaft 21 that is provided at its ends with rearwardly projecting cranks 27, 27' which are bent into hooks forming crank pins and are in rigid relation to the arm 26. In the kinematic views, Figs. 15 to 19, the roller 25 is indicated by a short arc which is in contact with the arm 26 in all positions excepting the resetting position *b* shown in Fig. 19. Said roller being journaled on the trolley fulcrum pin 20 swings with the upper limb of the fulcrum heel 23, 23' and shifts toward and from the arm 26 which is fixed to the crank pin 21 and which is moved forward by said roller to turn the crank pin to force the crank arm down

when the trolley pole flies up from the wire and slides forwardly endwise, under the recoil of the springs.

28, 28' designate a bifurcated latch pivoted to the trolley foot at 29 and normally held in latching position by a spring 30 which engages underneath the bar 31 of the latch. The latch 28 and 28' corresponding to the heel is made in two duplicate parts shown clearly in Figs. 2 and 3 and said parts extend under the lower tips of the heel 23, 23' as seen in Fig. 11. From the nature of the view in Fig. 10 the heel pieces are not in that view clearly shown as being distinct from the latches which 80 they partly cover as the parts are superposed in such a manner that full illustration of the same by dotted lines in this view is not practical. The duplicate parts of the latch 28 and 28' are notched at their 85 free ends to normally hold the tips of the heel 23, 23' and to release said heel when the latch is depressed by the means herein-after described. The heel composed of said two parts 23, 23' is thus pivoted to turn 90 on the heel journal 19; and the trolley fulcrum pin 20 is thus pivotally mounted through the medium of the heel 23, 23' upon the heel journal 19 that is carried by the standards 14 and 14'; and when the 95 heel is unlatched said fulcrum pin may move forward and back on an arc described from said journal 19 and carries the trolley pole forward and back with it. The spring 30 is a leaf spring bolted to the base and 100 extending between the lower tips of the heel and between the members 28, 28' of the latch. The tension of the spring is upward on the bar 31, which is rigid with the two members 28, 28' of the latch. When 105 the heel is latched the trolley-fulcrum 20 is held retracted from the arm 26.

32, 32' designate the trolley springs which are attached to the free ends of the cranks 27, 27' and to lugs 33, 33' on the trolley-pole 110 socket-piece 34 of which the shank 24 is a part, and which socket-piece carries the trolley-pole 3. The tendency of the springs 32, 32' is to draw the trolley-pole to upright position, and also to draw the arm 26 115 against the roller 25 so long as the fulcrum 20 is held retracted by the latched heel 23. This will be understood by reference to Figs. 15 and 16.

By reference to Figs. 10, 11, 15, 16 and 17 120 it will be seen that when the heel 23 is unlatched, thus allowing the force of the spring 32 and the weight of the trolley-pole 3 to shift the fulcrum 20 forward along the slot 16, the roller 25 will force the arm 26 125 forward, thus forcing the cranks 27, 27' downward, thereby shifting the lower end of the spring 32 and bringing it almost in line with the axis of fulcrum 20, thereby greatly reducing the leverage of the spring 32 so 130

that its tendency to lift the trolley-pole is less when the heel is unlatched and the fulcrum advanced as in Fig. 17 than when the heel is latched and the fulcrum retracted as 5 in Figs. 12 and 15.

35 designates a latch-releaser adapted to be operable by a sudden upward movement of the trolley-pole such as will occur when the trolley-wheel accidentally leaves the 10 trolley-wire 5. Various contrivances for effecting such release of the latch may be provided. For this purpose 36, in a general way, designates a liquid-container, and 37 a mobile body of liquid therein. Glycerin is 15 a suitable liquid for such body. The purpose of the mobile body is to allow any amount of normal up-and-down movement of the trolley-wheel to occur without affecting the latch-releaser 35, but to cause the latch-releaser to operate to release the latch immediately the movement of the trolley-wheel in response to the springs 32, 32' is 20 unrestrained. The liquid body and the related elements constitute rate-gaged means 25 whereby the excessively speedy movement of the trolley-pole is caused to release the same. A distinctive and basic feature of this invention resides in the provision therein of means by which the trolley springs will 30 upon a sudden upward movement of the trolley pole within the working range of such pole automatically act to start the upper end of the trolley pole to swing downward. Heretofore the downward movement 35 of the pole has only been effected by mechanical engagement of parts which cannot engage until the pole has reached a determined point in its upward movement, while 40 with this invention I interpose means which operate by reason of any sudden movement of the trolley pole instead of by engagement of moving parts after the trolley pole has reached a determined point in its upward movement. In the drawings I have shown 45 the best means by which I contemplate effecting this operation, but it is evident that the invention is not to be limited to the specific means for this purpose which I have herein incorporated as a part of the novel 50 apparatus.

38 designates a flexible diaphragm operable by said body, 37. The same may be a sheet of leather or other suitable flexible material fixed between the trolley-foot 10 and 55 an open-ended cylinder 39 that forms a part of said container and is fixed to the trolley-foot by means of bolts 40. The latch-releaser 35 may be mounted in a chamber 41 in the trolley-foot, and is movable up and 60 down to force the diaphragm 38 upward against the mobile body 37, and in turn to be forced downward thereby.

A piston 42 having bypass ways 43 controlled by a valve 44 is provided in the container 36, and adapted to move freely there-

in toward and from the diaphragm 38 when the bypass ways 43 are open. The valve 44 is arranged to normally leave the bypass ways 43 open, said valve being arranged to fall away from the piston 42 by gravity, and 70 also being provided with a spring 45 to assist such movement, thus normally leaving the ways 43 open so that the piston may move up and down in the container 36. The valve is so arranged below the bypass ways 75 43 that upon a sudden downward movement of the piston 42 the liquid body 37 will hold the valve 44 until the piston reaches it, thereby suddenly closing the bypass ways 43, whereupon any force applied to further 80 move the piston toward the diaphragm 38 will force said diaphragm downward to move the latch-releaser 35 downward, thus to release the latch 28 from latching position and allow the lower portions of the 85 heel pieces 23 which have been held by said latch, to move backward. This allows the upper portion of the heels to move forward in response to the tension of the springs 32, 32'. The piston 42 is connected with the 90 trolley-pole above the heel-pin 20 through a piston-rod 46 loosely pivoted to a lever 47 that is fulcrumed on the journal 22 and is provided at one end with a slot 48 to accommodate a pivot 49 of the piston-rod 46; 95 said lever being pivotally and loosely connected by links 50, 50' with the shank of the trolley-pole.

51 designates the pivot between the links 50 50' and the lever 47, and 52 designates 100 the pin between the links and the trolley-pole shank-piece 24' that forms part of the shank of the trolley-pole and is set in the end of socket-piece 34. The pin 52 is fixed to said shank-piece 24' and plays in a slot 53 105 in the links. 54 is a spring engaging a bar 55 which is rigidly connected with both of said links. Said spring tends to force the links toward the trolley pole shank and to operate the lever 47 to resiliently retract the 110 piston 42.

In Fig. 12 the parts are shown in solid lines in the positions occupied after the force from the upward thrust of the trolley-pole has been transmitted through the pins and 115 links 51, 52 and 50, the lever 47, thence through piston-rod 46, liquid body 37, diaphragm 38, and latch-releaser 35 to the latch 28 which has thereby been forced downward from the trolley-heel 23, thus releasing the 120 same, and the trolley-fulcrum or heel-pin 20 has moved from the dotted position *d* at one end of the slot 16 downward and forward to the position shown in solid lines, and the roller 25 has been forced downward and forward, thus moving the arm 26 forward from the dotted position *d*, and bringing the spring 32 close to the axis of the fulcrum so that the leverage of the spring to lift the pole has been reduced from what existed 130

while the trolley-heel was latched. Whenever the trolley-pole-fulcrum 20 and the roller 25 thereon shift forward relative to the journals 21 and 19 which are stationary, 5 the roller 25 acts upon the arm 26 of the spring-crank-shaft 21 and shifts the cranks 27, 27' to shift the draft-line of the springs 32 relative to the fulcrum of the trolley-pole, thus to decrease and increase the lifting 10 effect of the spring as required for different operations of the pole. In the working position *c* shown in broken lines in Figs. 11 and 12, and indicated in Fig. 15, the latch 28 holds the tip of the heel 23 forward, thereby 15 holding the trolley-fulcrum in its rearmost position and thus allowing the spring tension arm 26 to travel backward, thereby allowing the pins of the spring-cranks 27, 27' to stand off center and above the fulcrum of the trolley pole, so that the draft of 20 the springs 32 is above the fulcrum and is operative to draw the trolley-pole upward. In case the trolley-wheel escapes from the trolley-wire the springs 32 rapidly draw the 25 trolley-pole upward, thus causing the pin 52 to move upward and forward in an arc from position *c* to a position *d*, thereby suddenly forcing the lever 47 into the position *d*, and the piston 42 down upon the check-valve 44, 30 thereby driving the liquid 37, the diaphragm 38, spring-releaser 35, and the latch 28 downward, thus releasing the tip of the heel 23. During this time the weight of the trolley-pole and the force of the springs are 35 effective to shift the fulcrum from position *d* to *e*, thereby forcing forward the crank-arm 26, thereby turning the crank-shaft on its axis and forcing the cranks 27, 27', downward, thus bringing the draft line of the 40 springs nearly in line with the trolley-fulcrum so as to reduce the upward pull on the pole and direct the force to move the pole endwise rather than upward, and to tilt the fulcrum-carrying portions of the heel forward 45 over the journal 19, thereby continuing to move the crank-arm 26 forward and the cranks 27, 27' downward into line, or nearly so, with the fulcrum, so that the force 50 of the springs 32 to lift the trolley-pole is greatly reduced and becomes insufficient to sustain the weight of the trolley-pole. Since the trolley-heel is now fully released, said heel turns on the fulcrum formed by the pin 20 and allows the pole to descend. During 55 the forward endwise movement of the trolley pole caused by the recoil of the springs the operation relative to the lever 47 after the trolley pole is released by escape of the trolley wheel from the wire, is as follows: 60 At first the lever 47 moves sufficiently to force the piston rod 46 down until the heel 23, 23' is unlatched; and, the valve 44 being closed, the piston rod 46 is held against further downward movement, thus holding the 65 lever 47 rigidly against the upward endwise

thrust of the link 50 so that as said link 50 swings forward the pin 52, by which the link 50 is pivoted to the trolley pole 24, must descend. The pin 20 necessarily moves in an arc of a circle whose center is the journal 19 and hence a limitation of its movement aside from moving in the arc is impossible. When the latch 28 releases heel 23 the trolley pole is acted upon by the spring 32 operating from pin 21 and the pole is free to move 70 about the fixed point or axis formed by journal 19, and the now fixed pivot point 51, and in the movement of the pole the pin 20 and the pin 52 on the pole must move in arcs of circles about these fixed points 20 and 51, 75 the radii being the upper part of heel 23 between pin 19 and pin 20 and the links between pin 52 and pivot 51; and the distance between pin 20 and pin 52 must of course always be the same. Under these conditions 80 although both points on pole 20 and 52 move forwardly and downwardly the pole 3 extended rearwardly through these points will describe at its end a downward as well as a forward movement. As soon as the link 50 has come to the position *e* shown in dotted lines in Fig. 16 and in solid lines in Fig. 17 85 the pole may move on to the position shown in Fig. 18.

It is to be understood that in this specification the movement of the trolley pole on its horizontal pivot is spoken of as the "upward and downward movement of the trolley pole," meaning the effectual movement of the upper or main part of the pole above 90 the horizontal pivot.

The trolley-heels 23, 23' are each provided with a shoulder 58 beneath the trolley-pole-shank 24 which is forked to embrace the trolley-heels and to come to rest thereon 105 when the trolley-pole has descended to the resting position *a*.

Refer now to Fig. 18. When the trolley-shank 24 engages the shoulders 58 of the trolley-heel, it thereby tends to swing the 110 trolley-fulcrum 20 backward, which can only be done by stretching the spring 32. The momentum of the trolley-pole is insufficient to thus stretch the spring, and therefore the trolley-pole is held in the resting position *a* until additional force is exerted, as by the conductor or other attendant, through the trolley-rope *r* to pull the trolley down into the position *b* shown in solid lines in Fig. 11. The movement thus 115 effected by pulling down the pole from resting position to resetting position, Fig. 19, can be traced in said Fig. 11 by means of the broken lines. Referring now to Figs. 18 and 19, when force is applied through the 120 trolley rope *r* to pull the trolley wheel 4 down the trolley pole operates the lever 47 to raise the piston, and at the same time forces the shoulder 58 downward and consequently the heel 23 forward allowing the 125 130

spring 30 to lift the latch 28 and thereby latching the heel. At the same time the fulcrum pin 20 and the roller 25 move rearwardly. The rearward movement of the fulcrum and roller allows the crank-arm 26 to move rearwardly and the cranks 27, 27' to move upwardly until the draft of the springs comes well above the trolley-fulcrum. The free end of the latch 28, 28' and 10 the lower ends of the heels 23, 23' are beveled as shown in Figs. 11 and 12 so that as the lower tips of the heel move forward they force the latch down against the tension of spring 30 which returns the latch to latching 15 position as soon as the tips 23, 23' have passed into the notches of the latch. The downward movement of the shoulders 58 shifts the tip of the heels 23, 23' into latching position, thereby giving a purchase for 20 the heel so that as the trolley-rope is paid out the trolley-pole will travel upward, the trolley-fulcrum having been given a fixed support. As the ends of the cranks 27, 27' rise above the fulcrum, the effect of the 25 spring to lift the trolley-pole is increased without increased tension of the spring after the setting operation has been performed by the attendant.

56 and 57 are buffers of rubber or other 30 suitable material; the buffer 56 being annular and located in the chamber 41 to receive the latch-releaser 35 which is flanged to rest on said buffer to relieve the shock resulting from the sudden closing of the by-pass 43. Said buffer 56 operates through flanged 35 latch-releaser 35, the diaphragm 38, the liquid body 37, the valve-piston 42, piston-rod 46, lever 47, and links 59, to stop the sudden upward travel of the trolley-pole, 40 and, by reason of its resiliency, to assist somewhat in returning the pole from its uppermost position. The buffer 57 is a rubber block located on the base underneath the dog-arm 62 to be engaged by said dog-arm 45 when the same is forced down by the crank-arm 26.

In order to prevent the trolley pole from swinging greatly to one side or the other, after the trolley wheel becomes free from the 50 trolley wire two pairs of stops in the form of studs 59 are provided, one pair at the front and the other at the back of the trolley base 6, and a dog 60 is pivoted to the trolley foot 10 and is arranged to project into position 55 between a rearward pair of said studs 59, which project upwardly from the base to restrict the rotation of the trolley foot within certain limits. It is desirable however that the trolley pole be free to swing at all 60 times, except when uncontrolled, either by the trolley wire, or by the trolley rope. To effect this result the dog 60 is pivoted on the heel journal 19 and is provided with three arms, 61, 62, 63. The arm 61 is adapted to 65 enter and withdraw from between the studs

59. The arm 62 is adapted to be depressed by the crank arm 26 when the same is forced forward by the trolley pole, thereby to lift the arm 61 into the dotted position shown in Fig. 11, and the solid position shown in Fig. 70 12, ready to engage one or the other of the studs 59 as the trolley foot rotates in one or the other direction. The arm 63 is adapted and arranged to be engaged by the crank arm 26 when the trolley is in the working 75 position c. Since the trolley pole moves into the forward position e almost instantly after the trolley wheel leaves the trolley wire, it is apparent that the crank arm 26 thus immediately throws the dog 60 into the 80 stop engaging position, and as the trolley pole remains in the forward position, thus holding the crank arm 26 from that time until the trolley pole has been depressed to the setting position, it is evident that the dog 60 85 will remain in stop engaging position approximately from the time the trolley wheel has escaped from the wire, until it is under the control of the trolley rope. When the trolley is reversed the other pair of studs 90 will stop the dog. Whenever the crank arm 26 operates to force the dog arm 62 downward said dog arm comes to rest on the rubber buffer 57, thus preventing jars. When the trolley pole is drawn down into the re-setting position b thereby retracting the trolley pole into the position shown in solid lines, Fig. 11, the arm 26 is thus left free to move rearwardly when the draft line of the 95 springs comes into position to swing the 100 crank pin upwardly. The crank arm 26 at this time comes into position between the arms 62 and 63, of the dog 60 and allows said dog 60 to drop out of its stop-engaging position. When the trolley pole has risen 105 sufficiently to allow the draft line of the springs to come above the trolley fulcrum, then the crank arm 26 becomes retracted into the position c, seen in broken lines Fig. 11. When the crank arm engages the dog arm 110 63 it holds the same rearwardly thus to hold the arm 61 down out of stop engaging position, thus to leave the trolley foot free to rotate on its vertical axis until the crank arm is again shifted by tripping of the pole, or 115 by such lowering of the same as will release the dog 60.

I claim:

1. A retrieving trolley comprising a trolley pole, springs normally in commission to uplift the trolley pole, a fluid containing cylinder, a piston for the cylinder, said piston being operable by movement of the trolley pole, a by-pass way to pass the fluid from one side of the piston to the other 120 side, a valve operable by movement of the piston to close the way, and means operable by pressure of said fluid to throw the springs out of commission. 125

2. A pivoted heel, a latch to hold said 130

heel, a pole fulcrumed on said heel, a spring arranged to raise the pole, means operable by the shifting fulcrum to change the draft line of the spring to reduce its lifting effect on the pole, and means to release the latch to allow said heel to shift, thereby to shift the fulcrum and change the draft line of the spring.

3. A rotatable foot, a pivotally mounted trolley pole carried thereby, means to restrict the rotation of the foot, means to swing the pole upward, a latch to retain said pole-swinging means and pole in pole-supporting position relative to each other, and means operable by rapid movement of the pole to release said latch and to move the restricting means into commission.

4. A trolley pole mounted to swing on a vertical axis and also on a horizontal axis, means for swinging said pole on the horizontal axis into operative position, and means operable by the movement of the pole to automatically lock the pole against swinging on the vertical axis when the pole is out of operative position.

5. A pivoted trolley-foot provided with two upwardly - projecting standards, a trolley-pole pivotally connected with said standards, a dog pivoted to the standards, stops, and means operable by the trolley-pole to move the dog into position to engage the stops when the trolley-pole is unrestrained.

6. A trolley-pole, a shiftable fulcrum on which the trolley pole is pivoted, an arm operable by the trolley pole, a crank in fixed relation to such arm, and a spring connecting the pole with the crank to lift the pole and movable by the crank toward and from the fulcrum to decrease and increase the lifting effect of the spring on the pole.

7. A pole, a shiftable fulcrum therefor, means to hold the fulcrum stationary, a releaser therefor, a liquid body to operate the releaser, a piston provided with a valved bypass to move the liquid body, and means for transmitting power from the pole to the piston to cause the liquid to operate the releaser at a rapid movement of the piston.

8. The combination of a pivoted heel, a trolley-pole fulcrumed thereon, a crank, an arm in fixed relation to the crank and operable by the movement of the fulcrum, a spring connecting the pole and crank, a latch for the heel to hold the same in position with the spring in position to exert a definite lifting force on the pole, a releaser for the latch, a confined body of liquid ar-

ranged to operate the releaser, a valved piston adapted to cause the liquid to operate the releaser when the piston moves toward the releaser at a definite speed, means to transmit motion from the trolley-pole to the piston to cause the releaser to release the latch and thereby allow the heel to turn to shift the crank to reduce the lifting force of the spring.

9. The combination with a trolley-pole, a spring therefor and means to shift the spring to increase and decrease its lifting force, of a confined body of liquid to set into operation the spring-shifting means, a piston to actuate the body, a lever to operate the piston, a slotted link to operate the lever, a pin in the slot and operable by the trolley-pole to move the lever in one direction, and a spring carried by the pole to move the lever in the other direction.

10. The combination with a pivoted heel, of a spring, a latch to engage the heel to hold the heel in pole-supporting position, a trolley pole pivotally mounted on the heel and adapted and arranged to be supported by the heel and spring when the heel is latched, and to engage the heel to bring the same to latching position, and means operable by rapid movement of the pole while the pole is within its normal range, to release the latch.

11. The combination with the trolley-base provided with a stop, of a trolley-foot rotatable thereon, a dog on the foot to engage the stop to lock the foot relative to the base, a pole fulcrumed on the foot, means to hold the pole in working position, and means operable by the pole to hold the dog out of locking position when the pole is in working position, and to hold the dog in locking position when the pole is unrestrained.

12. A base provided with a stop, a rotatable trolley-foot on the base, a dog on the trolley foot provided with three arms, one of which is adapted to engage the stop to lock the foot against rotation, a trolley-pole, and means operably connected therewith to act upon the other arms to move the dog into and out of locking position.

In testimony whereof, I have hereunto set my hand at Oakland, California, this 13th day of June, 1908.

CHARLES EUGENE LANG.
